United States Patent Office

Des. 183,889
Patented Nov. 11, 1958

183,889

VEGETABLE AND FRUIT CUTTING MACHINE OR SIMILAR ARTICLE

Michael H. Juliano, Watertown, Mass.

Application November 26, 1956, Serial No. 43,933

Term of patent 7 years

(Cl. D89—1)

Fig. 1 is a front elevational view of my vegetable and fruit cutting machine,

Fig. 2 is a side elevational view thereof,

Fig. 3 is a rear elevational view thereof,

Fig. 4 is a top plan view thereof, and

Fig. 5 is a perspective view thereof.

I claim:

The ornamental design for a vegetable and fruit cutting machine or similar article, substantially as shown.
